UNITED STATES PATENT OFFICE.

CHARLES A. ROBINSON, OF HEMPSTEAD, NEW YORK, ASSIGNOR TO THE IDEAL FUEL FEEDER COMPANY, OF SAME PLACE.

NOZZLE FOR FEEDING FINE FUEL TO FURNACES.

SPECIFICATION forming part of Letters Patent No. 639,437, dated December 19, 1899.

Application filed August 29, 1899, Serial No. 728,881. (No model.)

To all whom it may concern:

Be it known that I, CHARLES A. ROBINSON, a citizen of the United States, residing at Hempstead, in the county of Nassau and State of New York, have invented certain new and useful Improvements in Nozzles for Feeding Fine Fuel to Furnaces; and I do hereby declare the following to be a full, clear, and exact description of the invention, such as will 55 enable others skilled in the art to which it app pertains to make and use the same.

My invention is an improvement in twyers or nozzles for feeding finely-divided fuel to furnaces; and it consists in the novel features 55 hereinafter described.

In the accompanying drawings I have illustrated one form in which I have contemplated embodying my invention, and my invention is fully disclosed in the following description 20 and claims.

Referring to the said drawings, Figure 1 represents a perspective view of my improved twyer or nozzle, taken from the end outside of the furnace. Fig. 2 is a perspective view 25 of the twyer or nozzle, taken from the end which projects into the fire-box or combustion-chamber. Fig. 3 is a central vertical sectional view of the device, showing it provided with two sets of horizontally-disposed 30 deflectors. Fig. 4 represents a horizontal sectional view of the twyer or nozzle, a portion being broken away.

In feeding finely-divided fuel to furnaces with and by means of a blast or current of air it is extremely difficult to secure a perfectly-even distribution of the fine fuel as it leaves the twyer or discharge-nozzle, owing to the fact that the fuel being heavier than the current of air has a tendency to settle or precipitate before it leaves the nozzle. It is also difficult to secure exactly the required quantity of air to effect a perfect and smokeless combustion of the fine fuel and to regulate the air-supply accurately in proportion to the 45 amount of fuel being fed.

The object of my invention is to overcome these difficulties by remixing the air and fuel immediately before it leaves the nozzle or twyer, to distribute the fuel evenly throughout 50 the entire width of the furnace or combustion-chamber, to regulate the air-supply

so that it will at all times be in proper proportion to the amount of fuel being fed, and also to retard the discharge of fuel and air from the nozzle, so that the flame produced 55 within the combustion-chamber or fire-box will travel more slowly therethrough, and thereby impart its heat more fully to the boiler than it would if discharged at the initial velocity of the air blast or current. 60

In the drawings, in which I have illustrated one form of twyer or nozzle embodying my invention, A represents the shell or main body of my improved twyer, which may be formed of sheet or cast metal in one single piece, as 65 shown in the drawings, or in several pieces suitably united, as may be found most desirable and convenient. This shell or main body is rectangular in cross-section and is narrowed vertically and expanded laterally 70 from the outside end to the inside end, as shown.

The outer end or wall a of the shell or main body is provided centrally with a neck a', having a passage therethrough, in this instance 75 rectangular in cross-section, to which is connected the pipe or chute for supplying the air and fine fuel. Above this neck a' the said wall a is provided with a horizontal opening a², and a similar opening a³ is provided below 80 the neck a'.

The lateral walls or cheeks a⁴ a⁴ of the shell are provided with large air-inlet openings a⁵ a⁵, which are adapted to be partially or wholly closed by adjustable closing-plates or dampers B B, the positions of which can be regulated by means of a suitable clamping-screw or similar device. In the present instance I have shown each of the side faces a⁴ provided with a central portion a⁶, extending across the 90 aperture a⁵ and provided with a slot a⁷, which is engaged by a sliding clamping-bolt b, which also passes through the closing-plate B and is provided with a clamping-nut, a wing-nut being shown. By loosening this nut the 95 plate B may be moved so as to close more or less the opening a⁵, and thereby regulate the admission of air into the nozzle and so into the combustion-chamber.

The outer end or wall a of the shell or main body is provided at each end of the lower aperture a³ with a bearing or socket c, in which

is mounted a supporting-shaft C, extending across the aperture and secured in said bearings by set-screws c'. Upon the shaft C is mounted one or more horizontally-disposed deflecting-plates capable of angular adjustment upon the shaft C. I may use a single plate or any number; but I prefer to employ three plates, as shown and indicated by D' D² D³. Each of these plates is pivotally and adjustably connected to the shaft C, and I prefer to secure each plate by riveting or otherwise to a sleeve or collar D, surrounding the shaft C and provided with a set-screw d for securing it in its adjusted positions. I also prefer to form the central plate D² with parallel lateral edges and to make the outer lateral edges d' d³ of the outer plates D' D³ inclined to correspond to the inclination of the lateral faces or cheeks a⁴ a⁴ of the shell or main body, as clearly shown in Fig. 4. The deflecting-plates D' D² D³ are of such length that they can be turned up into the path of the current of air and fuel passing through the neck a' and independently adjusted, so as to deflect it upward toward the upper wall a⁸ of the shell or main body.

The opening a² above the neck a' may be left unobstructed as an air-opening, or I may provide the exact duplicates of the independently-adjustable deflecting-plates D' D² D³ and connected parts above the neck a', as shown in Fig. 3, so that the current of air and fuel may be deflected downward toward the bottom plate a⁹ of the shell or main body, if found necessary or desirable. It will of course be obvious that if any of these plates are not needed they can simply be turned parallel with the adjacent upper or lower wall of the main body and will then have no effect upon the air and fuel. It will also be observed that air is permitted to enter through the openings a² a³ to mingle with the fuel and assist in producing a perfect combustion of the same.

I also provide at and adjacent to the inner end of the twyer or nozzle adjustable devices for securing the proper mixture and lateral distribution of the air and fuel and for retarding the discharge of the air and fuel to reduce the velocity of the flame and products of combustion in their passage through the furnace. These devices consist of a plurality of vertically-disposed plates arranged angularly with respect to the longitudinal axis of the nozzle. I prefer to provide two rows or series of these vertically-disposed retarding and spreading plates, one series adjacent to the bottom plate a⁹ and the other adjacent to the upper plate a⁸ of the nozzle, each plate of one series being disposed angularly to the corresponding plate of the other series. In the drawings I have shown four plates in each series; but I do not limit myself to any particular number, nor do I limit myself to the exact arrangement of said plates herein shown and described. In the present instance the bottom plate a⁹ is provided with four verti-

cally-disposed plates E' E² E³ E⁴, each of which is provided at its lower edge with a lateral flange E, pivoted to the bottom plate a⁹ 70 at e. Adjacent to each of said plates the bottom plate a⁹ of the nozzle is provided with a curved slot a¹⁰, and each of the flanges E is provided with a clamping-bolt e', passing through one of said slots a¹⁰ and through the flange E and provided with a nut e². By this means these plates may be swung on their pivots e to their desired positions and clamped rigidly in position by the bolts e' and nuts e². I prefer to arrange the central plates E² E³ so 80 that they converge slightly and the plates E' and E⁴ to diverge from their adjacent plates E² and E³, respectively, as shown in full lines in Fig. 4. The upper plate a⁸ is provided with four vertically-disposed plates F' F² F³ 85 F⁴, constructed exactly like the plates E', &c., having flanges F, pivoted at f and provided with clamping-bolts f' and nuts f², said bolts passing through curved slots a¹⁰ in the upper plate a⁸. The lower edges of the plates F', 90 &c., are in substantially the same plane as the upper edges of the plates E', &c., and each of plates F' F² F³ F⁴ is disposed at an angle opposite to that of the corresponding plate beneath it, as indicated in dotted lines in Fig. 95 4, and also clearly shown in Figs. 1 and 2. The two central plates F² F³ will therefore diverge, while the plates F' F² and F³ F⁴ will converge. The arrangement of the plates of the two horizontal series at different angles, 100 as shown and described, enables these plates to coöperate with the horizontally-disposed deflectors D' D² D³, as by adjusting the latter to throw the material up or down or partly up and partly down different results in the 105 lateral distribution of the material are obtained and the desired even and uniform discharge of the material can be accurately obtained. It will also be seen that in passing the spreading and retarding plates the air 110 and fuel will be retarded just prior to their delivery from the nozzle, thus causing the flame within the combustion-chamber to travel more slowly and enabling it to give off its intense heat more fully to the boiler. The 115 apertures a² a³ will allow a considerable amount of air to enter the nozzle and unite with the current of air and fuel, and the lateral adjustable openings a⁵ a⁵ will also supply a large volume of air, so that the proper 120 amount for producing complete and smokeless combustion of the fuel can be obtained.

The shell or main body A is also provided with an outwardly-extending flange A', perpendicular to the longitudinal axis of the 125 nozzle, by means of which it is secured to the furnace. I preferably form an aperture in the ordinary fire-door, through which the inner end of the nozzle is inserted until the said flange A' abuts against the door, and the nozzle is secured in position by bolting the said flange to the door, the bolts passing through bolt-holes A², formed in said flange.

I do not limit myself to the exact details of

construction herein shown, as slight variations may be made therein without departing from the spirit of my invention.

What I claim, and desire to secure by Letters Patent, is—

1. In a nozzle for feeding fine fuel to furnaces, the combination with the hollow main body, of a series of independent, vertically-adjustable deflectors, extending transversely of the main body, each adapted to be moved into the path of the current of air and fuel, substantially as described.

2. In a nozzle for feeding fine fuel to furnaces, the combination with the hollow main body having a passage therethrough for the passage of a current of air and fuel, of a horizontal series of vertically-movable deflectors pivoted to said main body, and independent securing devices, for each of said deflectors, substantially as described.

3. In a nozzle for feeding fine fuel to furnaces, the combination with the hollow main body having a passage therethrough for the passage of air and fuel, a transverse shaft extending transversely of said main body, a series of independently-movable deflectors pivotally mounted on said shaft, and independent devices for holding said deflectors in fixed relation with said shaft, substantially as described.

4. In a nozzle for feeding fine fuel to furnaces, the combination with the hollow main body, of a series of vertically-disposed spreading and retarding plates located within said main body adjacent to the delivery end thereof, said plates being separated from each other throughout their length to permit the fuel to pass between them, and independent adjusting devices for each of said plates, for adjusting them laterally, substantially as described.

5. In a nozzle for feeding fine fuel to furnaces, the combination with the hollow main body, of a vertically-disposed, laterally-adjustable spreading and retarding plate located in said main body adjacent to the delivery end thereof and devices for securing said plate rigidly in its adjusted position, substantially as described.

6. In a nozzle, for feeding fine fuel to furnaces, the combination with the hollow main body, of a vertically-disposed spreading and retarding plate located in said main body adjacent to the delivery end thereof and pivotally secured to said main body, and a securing device for holding said plate rigidly to the main body in its adjusted position, substantially as described.

7. In a nozzle for feeding fine fuel to furnaces, the combination with the main body, of a series of vertically-disposed spreading and retarding plates located adjacent to the delivery end of said main body, a second series of said plates located above those of the first series, each plate of each series being

disposed at an angle to the adjacent plate of 65 the other series, substantially as described.

8. In a nozzle for feeding fine fuel to furnaces, the combination with the main body, of a series of vertically-disposed spreading and retarding plates located adjacent to the 70 delivery end of said main body, a second series of said plates located above those of the first series, and independent adjusting devices connected with each of said plates, substantially as described.

9. In a nozzle for feeding fine fuel to furnaces, the combination with the main body, of a series of vertically-disposed spreading and retarding plates located adjacent to the 80 delivery end of said main body, a second series of said plates located above those of the first series, each plate of each series being disposed at an angle to the adjacent plate of the other series, and a horizontally-disposed, vertically-adjustable deflector located adjacent to the outer ends of said vertical plates, substantially as described.

10. In a nozzle for feeding fine fuel to furnaces, the combination with the hollow main body provided with an inlet-opening and a 90 discharge-opening, of a horizontally-disposed vertically-adjustable deflector adjacent to said inlet-opening, a vertically-disposed spreading and deflecting plate adjacent to the discharge-opening of said main body and 95 a vertically-disposed spreading and deflecting plate above and at an angle to said first-mentioned plate, substantially as described.

11. In a nozzle for feeding fine fuel to furnaces, the combination with the main body 100 having an inlet and a discharge opening, a horizontally-disposed vertically-adjustable deflector above and below said inlet-opening, a horizontal series of vertically-disposed spreading and retarding plates adjacent to 105 the discharge-opening of the nozzle, a second series of said vertical spreading and retarding plates above those of the first-mentioned series, each plate of the upper series being disposed at an angle to the corresponding plate 110 of the lower series, and independent adjusting devices for laterally adjusting each of said plates, substantially as described.

12. In a nozzle for feeding fine fuel to furnaces, the combination with the main body 115 having an inlet and a discharge opening, a horizontally-disposed, vertically-adjustable deflector above and below said inlet-opening, and a series of vertically-disposed spreading and retarding plates adjacent to the discharge-opening of the nozzle, substantially as described.

In testimony whereof I affix my signature in the presence of two witnesses.

CHARLES A. ROBINSON.
